[57] ABSTRACT

A closure for a container body includes a central panel having a removable portion defined by a line of weakness and a fixed portion surrounding the removable portion and secured to the container body. The fixed portion is detachably joined to the removable portion by an uninterrupted hollow bead disposed below the plane of both portions, the bead having a transverse cross section defining an open top channel. One edge of the opening of the channel is connected to the removable portion at the line of weakness, and the other edge of the opening is connected to the fixed portion, the channel affording entrance for a conventional can closure opening tool which separates the removable portion from the bead at the line of weakness.

PATENTED SEP 24 1974

3,837,523

FIG. 1

FIG. 2

BEADED CLOSURE FOR CONTAINERS

BACKGROUND OF THE INVENTION

1. Field of the Invention

The invention relates generally to containers of the type having closures provided with a line of weakness which may be readily fractured to provide access to the interior of the container. The line of weakness is located adjacent a bead connecting a removable central portion and a fixed portion secured to the container body, the bead providing a channel for insertion of an opening tool thereinto which fractures the line of weakness for access to the container.

2. The Prior Art

The prior art patents disclose structures whereby the central panel of the container closure is removed by the operation of a pull tab. In the structure according to the present invention, access to the container contents is achieved by manipulation of a conventional container opening device, and upon removal of the central panel of the closure, access is readily provided to the container contents, at the same time a remnant bead being provided enabling the hand to enter the container without danger of injury thereto by a raw edge resulting from the removal of the center panel.

Structures of the general kind are exemplified in the following patents:

SUMMARY OF THE INVENTION

The structure according to the present invention includes a central removable panel defined by a line of weakness connecting a central panel portion to a portion of the closure which is fixed to the container body, the line of weakness being located at a bead defining an open-topped channel enabling a tool to enter the channel and to cause a fracture of the line of weakness. The bead remaining after the removal of the central panel protects the hand entering the opened container.

THE DRAWING

FIG. 1 is a plan view of a closure according to the present invention; and

FIG. 2 is an enlarged transverse sectional view showing the closure in position on a container body.

SPECIFICATION

The improved closure is referred to by the reference numeral 10 and is shown in FIG. 2 as secured to a con-

tainer body 11. The closure 10 includes a central panel 12 having a removable portion 13 and a fixed portion 16, the closure 10 being secured to the container body by a conventional double seam 19. A vertical annular portion 17 connects the fixed portion 16 to the seam 19. A bead 18 having a transverse cross section defining a channel with an uninterrupted opening 21 therein connects the removable portion 13 with the fixed portion 16. One edge of the opening of the channel-shaped bead 18 is connected to the removable panel 13 at the line of weakness 14, and the other edge of opening 21 is connected to the fixed portion 16. Bead 18 lies below the plane of central panel 12.

Opening 21 of the channel-shaped bead 18 affords entrance for a conventional can opening tool so that the removable panel can be separated from the bead 18 at the line of weakness 14. The tool may be in the form of a conventional, manually operated can opener or in the form of a rotary type opener having a cutting wheel entrant at opening 21 as is well known.

The removal of portion 13 results in the bead 18 remaining in position with the torn edge resulting from the fracturing of the line of weakness 14 being protected. Obviously, bead 18 affords protection of a hand into the container body 11 after the removal of portion 13.

We claim:

1. In a closure for a container having a container body:
  - a. a central panel having:
    - i. a removable portion defined by a line of weakness;
    - ii. a fixed portion surrounding the removable portion and secured to said container body;
  - b. said fixed portion being detachable joined to the removable portion by an uninterrupted hollow bead disposed entirely below the plane of said removable portion;
  - c. said hollow bead having a transverse cross section defining a generally toroidal-shaped open-topped channel;
  - i. said hollow bead having an edge which is turned toward said fixed portion and which is connected to said removable portion at said line of weakness;
  - d. said open-topped channel affording entrance for a tool separating said removable portion from said bead at said line of weakness;
  - e. said open-topped channel remaining in position upon removal of said removable portion and having a raw edge at the opening thereof which is turned away from the opening resulting from removal of said removal portion.
